UNITED STATES PATENT OFFICE.

CLARKE R. LAKE, OF PEORIA, ILLINOIS.

COIN-CONTROLLED LOCK FOR LOCKERS.

Original application filed October 8, 1923, Serial No. 667,185. Divided and this application filed October 20, 1924. Serial No. 744,607.

To all whom it may concern:

Be it known that I, CLARKE R. LAKE, a citizen of the United States, residing at Peoria, in the county of Peoria and State of Illinois, have invented certain new and useful Improvements in Coin-Controlled Locks for Lockers, of which the following is a complete specification.

This invention relates to coin controlled locking means for lockers, and is made especially for collapsible great doors or other vertically sliding doors such as shown in my application filed October 8, 1923, Serial Number 667,185, of which this application is

15 a division.

The primary object of this invention is the provision of a coin controlled lock for lockers, wherein a coin, disk or check of any desirable shape, size and diameter may be used, and wherein the varying of the diameter of said coin or disk may be utilized to an advantage in assigning a different locker to an individual.

A still further object of this invention is 25 the provision of a coin controlled and actuated release for lockers or locker latches which may be placed within and near the top of the locker shown and described in the above mentioned application previously filed, and which may have a passage for the releasing coin communicating with a locked container under the floor of the locker.

An even further object of the invention is 30 to provide a desirable lock which is made of but few parts, is cheap to make and install, and is not likely to get out of order.

With these general objects in view, as well as minor objects which will appear in the course of the detailed description, the invention will now be described by reference to the accompanying drawings wherein similar reference characters refer to like parts throughout the several views, and wherein:

Figure 1 is a fragmentary horizontal central section of the lock member showing a coin in place ready for operation.

Fig. 2 is a cross section of the lock structure taken along line II—II of Fig. 1.

Fig. 3 is a vertical section of the coin

50 guide taken on line III—III of Fig. 1; and, Fig. 4 is a perspective view of the yoke construction and coin engaging foot showing the latch attached thereto.

This coin controlled lock is preferably installed in lockers having means for con-

veying the coin to a container, such as the integral passage 5 which may be built in adjacent the side 6 of the locker. The same is also installed near the top 7 of the locker where it will be best suited to hold a vertically sliding door having a latch lug 8 in position after the door has been closed.

In the illustration, the latch and its several parts are shown in a locked position with a coin 9 positioned in coin guide 10 which has an opening 11 formed therein, and which may be varied in size in the different lockers to suit the particular coin used.

A suitable plunger 12 having a transverse plunger pin 13 is slidably mounted in housing 14 with a retrieving spring 15. A slot 16 provides free passage for the pin 13.

When plunger 12 is forced inwardly against spring 15, coin 9 is carried to engaging foot 17 and forces it, with yoke 18, back to a point where latch 19 is carried inwardly against spring 20 to a point where latch lug 8 is released. Upon releasing plunger 12, coin 9 drops down through passage 5 to a suitable container not here shown. Any retrieving means may be used in place of the helical spring without departing from the invention.

The operation of the device is obvious from the foregoing description.

Having thus described the invention, what is claimed is:

1. A coin controlled lock for lockers, comprising a coin and plunger actuated releasing means for the lock including a yoke, coin engaging foot, a slotted coin guide, a slotted plunger housing means of retrieving said plunger carried by said housing and a manually operated plunger having a pin integral therewith and extending at right angles therefrom, said pin terminating in said coin guide to bear against the periphery of a coin whereby the same is forced against said coin engaging foot and rectilinear motion is imparted to said yoke.

2. A coin controlled lock for lockers, comprising a coin and plunger actuated releasing means for the lock including a slotted coin guide, a slotted plunger housing adjacent thereto, a plunger pin carried by a manually operated plunger disposed to project through the slots of said coin guide and plunger housing, a yoke having a coin engaging foot attached at one end and adapted

to engage said locking means adjacent the other end, said plunger pin extending at right angles to the direction of travel of said manually operated plunger and adapted to 5 bear against the periphery of a coin, whereby by actuating force is imparted to said yoke.

3. A coin controlled lock for lockers, comprising a coin and plunger actuated releasing means housed within and near the top of 10 said locker including a slotted coin guide, a slotted plunger housing adjacent thereto, a retrieving spring within said plunger housing, a plunger pin carried by said plunger and disposed to pass through the slots of 15 both the plunger housing and coin guide, a coin engaging foot, a yoke connecting said coin engaging foot and the locking means, retrieving means for said yoke and means for conveying the coin away from said releasing means, said coin guide having a portion 20 thereof projecting beyond the locker

wall whereby the coin may be inserted directly therein at a point behind said plunger pin.

4. In a coin controlled lock, in combination, 25 a yoke slidably mounted for rectilinear reciprocating movement only, locking means carried by one end of said yoke, a coin engaging foot carried by the other end thereof, both of said yoke ends extending forwardly and disposed in the same horizontal plane, a retrieving means engaging the locking means, a longitudinally slotted coin guide terminating adjacent said coin engaging foot, a slidably mounted plunger disposed between the ends of the yoke, a pin integral with said plunger and means for maintaining said plunger in a set position 30 substantially as set forth.

In testimony whereof I hereunto affix my signature this 3rd day of October, 1924.

CLARKE R. LAKE.
